UNITED STATES PATENT OFFICE

95,671

DESIGN FOR A CHAISE LONGUE

Paul T. Frankl, Los Angeles, Calif., assignor to Frank Debski, New York, N. Y.

Application February 20, 1935, Serial No. 55,520

Term of patent 3½ years

To all whom it may concern:

Be it known that I, Paul T. Frankl, a citizen of the United States, residing at Los Angeles, in the county of Los Angeles and State of California, have invented a new, original, and ornamental Design for a Chaise Longue, of which the following is a specification, reference being had to the accompanying drawing, forming part thereof.

I claim:

The ornamental design for a chaise longue, as shown and described.

PAUL T. FRANKL.
